METHOD OF PREPARING 3,3-DISUBSTITUTED-6-DIMETHYLAMINO-2-HEXANONES

Everett M. Schultz, Glenolden, Pa., assignor to
Merck & Co., Inc., a corporation of New JerseyNo Drawing. Application August 16, 1950,
Serial No. 179,896

3 Claims. (Cl. 260—570.8)

1

This invention is concerned broadly with certain new chemical compounds and with methods for their preparation. The invention is more particularly concerned with new methods for the production of 3,3-disubstituted-6-dimethylamino-2-hexanones, and 3,4,5,6-tetrahydropyridines methyl-substituted in the 2-position and disubstituted in the 3-position. Further, the invention is concerned with new substituted-2-hexanones obtained from the method of the invention. Additionally, the invention is concerned with new 3,4,5,6-tetrahydropyridines obtained as intermediate products in one step of the method of the invention.

The substituted-2-hexanones of this invention can be represented by the formula:

in which R is (1) alkyl up to and including lauryl, and preferably lower alkyl up to eight carbon atoms, and (2) mononuclear aralkyl, preferably benzyl, and Y is chosen from the group consisting of hydrogen, lower alkyl, halogen and alkoxy.

The tetrahydropyridines of this invention can be represented by the formula:

in which R' is (1) alkyl up to and including lauryl, and preferably lower alkyl up to eight carbon atoms (2) mononuclear aralkyl, preferably benzyl, and (3) mononuclear aryl, that is, C6H4Y, and in which Y is chosen from the group consisting of hydrogen, lower alkyl, halogen and alkoxy.

Heretofore, 3,4,5,6-tetrahydropyridines have been prepared by the cyclization of a δ -aminoketone, which aminoketones are difficult to obtain as the preparation is cumbersome and involved requiring several steps in the synthesis. Further, in the past, the hydrogenation of γ -cyanoketones, the starting materials of this invention, has yielded only completely saturated cyclic compounds, that is, piperidines. It has been discovered, as a feature of this invention, that, in the presence of Raney nickel catalyst, γ,γ -disubstituted- δ -oxocapronitriles can be hydrogenated so as to produce 3,4,5,6-tetrahydropyridines, which intermediate compounds can be trans-

formed to substituted-2-hexanones on treatment with formic acid and formaldehyde.

The complete process of this invention comprises hydrogenation of a γ,γ -disubstituted- δ -oxocapronitrile in the presence of Raney nickel catalyst at approximately 90-100° C. and at approximately 100 atmospheres pressure of hydrogen, to obtain 2-methyl-3,3-disubstituted-3,4,5,6-tetrahydropyridines. This step involves a feature of this invention and it is to be noted that the tetrahydropyridines so obtained are among the compounds of the invention. Thereafter, the tetrahydropyridines, which need not be isolated, upon treatment with formic acid and formaldehyde yield the desired, 3,3-disubstituted-6-dimethyl-amino-2-hexanones which are compounds of this invention. It is to be noted that this step involves a feature of this invention.

More particularly the hydrogenation step is carried out by admixing the appropriate oxocapronitrile (the preparation of which is described in my co-pending application entitled " γ,γ -Disubstituted- δ -oxocapronitriles") in a solvent such as absolute methanol or ethanol, adding thereto Raney nickel catalyst in an amount of from 2 to 10 grams per mole of oxocapronitrile and exposing this mixture to an atmosphere of hydrogen with agitation in a suitable reaction vessel at a pressure of approximately 100 atmospheres and at a temperature of from approximately 90-100° C. In general, the reaction is completed within approximately 1 to 2 hours, although certain oxocapronitriles require longer reaction time. Under these conditions, the absorption of hydrogen ceases when two moles of hydrogen per mole of oxocapronitrile has been absorbed. Utilizing the conditions of this invention and the Raney nickel catalyst, it has been discovered that little if any piperidine is formed and that substantially large proportions of the starting material is converted to the 3,4,5,6-tetrahydropyridine.

The above described hydrogenation is preferably carried out at 90-100° C. and at approximately 100 atmospheres pressure of hydrogen. It is to be noted that temperatures in excess of 100° C. will give decreased yields of the 3,4,5,6-tetrahydropyridines in that some of the tetrahydropyridine will be reduced further, that is, to the piperidine. It is to be realized that this hydrogenation can be carried out advantageously at pressure less than 100 atmospheres as the reaction depends not so much upon the pressure as upon the presence of hydrogen. Further, the temperature range of 90-100° C. is not critical, but is

preferred since at lower temperatures the rate of reaction is correspondingly less.

The tetrahydropyridine need not be isolated, but the purity and ease of handling the resultant aminoketone is facilitated by purifying the tetrahydropyridine. The tetrahydropyridine is dissolved in from 4 to 10 moles, and preferably 5 moles, of 90% formic acid per mole of tetrahydropyridine. To this is added, from 1 to 5 moles, and preferably 2.3 moles, of 37% aqueous formaldehyde per mole of tetrahydropyridine and the entire mixture is heated on a steam bath until evolution of carbon dioxide ceases. The evolution usually ceases in a period of time from approximately 3 to 10 hours, although the reaction for some compounds may fall outside these particular limits. After the evolution of carbon dioxide has ceased the reaction mixture is removed from the steam bath, cooled, and hydrochloric acid in an amount slightly excess of one mole of acid per mole of original nitrile starting material is added to form the hydrochloride salt of the 2-hexanone. The solution then is distilled to dryness under vacuum at approximately 100° C. The residue is taken up in the minimum amount of water sufficient to dissolve the residue and the solution washed with ether until clear.

The water solution of the 2-hexanone is made basic with sodium hydroxide solution. The product separates as an oil which is extracted with ether. The ether solution is dried over potassium carbonate and the potassium carbonate is separated by filtration. The ether then is evaporated and the residual oil is distilled under vacuum. There is obtained the desired 3,3-disubstituted-6-dimethylamino-2-hexanone.

The compounds of this invention are useful as intermediates for the preparation of a variety of chemical compounds. For example, from the 3,4,5,6-tetrahydropyridines there can be prepared the 3,3-disubstituted-6-dimethylamino-2-hexanones and 2-methyl-3,3-disubstituted-piperidines, which compounds possess physiological activity. For example, the 3,3-disubstituted-6-dimethylamino-2-hexanones possess anticholinergic activity.

The invention is illustrated by, but not necessarily restricted to, the following preferred embodiments.

Example 1—Preparation of 2,3-dimethyl-3-phenyl-3,4,5,6-tetrahydropyridine.—40.2 g. (0.20 mole) γ -methyl- γ -phenyl- δ -oxocapronitrile, 2.0 g. Raney nickel catalyst, and 100 ml. absolute ethanol were placed in a stainless-steel-lined, rocking autoclave. Hydrogen then was introduced into the autoclave to a pressure of 1350 pounds per square inch at 24° C. The autoclave then was heated to a temperature of approximately 90-100° C. and rocked or shaken to admix the contents. The heating was maintained and the rocking or shaking continued until the uptake of hydrogen ceased. The autoclave was cooled, and then the reaction mixture removed therefrom and filtered to remove the Raney nickel catalyst. The ethanol was evaporated from the filtrate and the residue taken up in approximately 100 ml. dilute hydrochloric acid. This acid solution was extracted with equal volumes of ether in order to remove unreacted nitrile. The removal of the nitrile was evidenced by the solution becoming clear. The solution was then made basic with sodium hydroxide, whereupon an oil separated. This oil was extracted with ether and the ether solution was dried over

anhydrous potassium carbonate. The potassium carbonate was removed by filtration and the ether evaporated. The residue was further purified by distillation under vacuum and there was obtained 2,3-dimethyl-3-phenyl-3,4,5,6-tetrahydropyridine, B. P. 80-83° C. at 0.5 mm. Hg, n_D^{25} 1.5437. The product was obtained in 81.5% yield. The bisulfate salt of this compound melts at 151.5-153° C.

Example 2—Preparation of 2-methyl-3-ethyl-3-phenyl-3,4,5,6-tetrahydropyridine.—Using the procedure outlined in Example 1 and a similar molar quantity of γ -ethyl- γ -phenyl- δ -oxocapronitrile in place of the γ -methyl- γ -phenyl- δ -oxocapronitrile there used, there was obtained a 71% yield of 2-methyl-3-ethyl-3-phenyl-3,4,5,6-tetrahydropyridine, B. P. 94-5° C. at 0.5 mm. Hg, n_D^{25} 1.5434. The hydrochloride salt melts at 148-50° C. The picrate salt melts at 127-8° C.

Example 3—Preparation of 2-methyl-3-n-propyl-3-phenyl-3,4,5,6-tetrahydropyridine.—Using the procedure outlined in Example 1 and substituting for the γ -methyl- γ -phenyl- δ -oxocapronitrile there used, an equimolar quantity of γ -n-propyl- γ -phenyl- δ -oxocapronitrile, there was obtained an 89% yield of 2-methyl-3-n-propyl-3-phenyl-3,4,5,6-tetrahydropyridine, B. P. 112° C. at 1.0 mm. Hg, n_D^{25} 1.5364. The bisulfate salt melts at 135.5-37° C.

Example 4—Preparation of 2-methyl-3-n-butyl-3-phenyl-3,4,5,6-tetrahydropyridine.—Using the procedure outlined in Example 1 and substituting for the γ -methyl- γ -phenyl- δ -oxocapronitrile there used an equimolar quantity of γ -n-butyl- γ -phenyl- δ -oxocapronitrile, there was obtained an 89% yield of 2-methyl-3-n-butyl-3-phenyl-3,4,5,6-tetrahydropyridine, B. P. 118.5° C. at 0.5 mm. Hg, n_D^{25} 1.5332. The bisulfate salt melts at 121-3° C.

Other examples of the preparation of 2-methyl-3-alkyl-3-phenyl-3,4,5,6-tetrahydropyridines will be apparent from considering that by substituting for the γ -n-butyl- γ -phenyl- δ -oxocapronitrile above used, equimolar quantities of γ -n-octyl- γ -phenyl- δ -oxocapronitrile and γ -n-lauryl- γ -phenyl- δ -oxocapronitrile there was obtained respectively 2-methyl-3-n-octyl-3-phenyl-3,4,5,6-tetrahydropyridine and 2-methyl-3-n-lauryl-3-phenyl-3,4,5,6-tetrahydropyridine.

Example 5—Preparation of 2-methyl-3,3-diphenyl-3,4,5,6-tetrahydropyridine.—Using the procedure outlined in Example 1 and substituting for the γ -methyl- γ -phenyl- δ -oxocapronitrile there used an equimolar quantity of γ,γ -diphenyl- δ -oxocapronitrile, there was obtained a 67% yield of 2-methyl-3,3-diphenyl-3,4,5,6-tetrahydropyridine, B. P. 128-30° C. at 0.5 mm. Hg, M. P. 106-7° C. The hydrochloride salt melts at 207-209° C.

Example 6—Preparation of 2-methyl-3-benzyl-3-phenyl-3,4,5,6-tetrahydropyridine.—Following the procedure in Example 1 and substituting for the γ -methyl- γ -phenyl- δ -oxocapronitrile there used, an equimolar quantity of γ -benzyl- γ -phenyl- δ -oxocapronitrile there was obtained a 69% yield of 2-methyl-3-benzyl-3-phenyl-3,4,5,6-tetrahydropyridine, B. P. 137-9° C. at 0.5 mm. Hg, M. P. 69.5-70.5° C. The hydrochloride salt melts at 218-220° C. The picrate salt melts at 174-5° C.

Other examples of the invention will be apparent from considering that by substituting for the γ -benzyl- γ -phenyl- δ -oxocapronitrile above used, equimolar quantities of γ -methyl- γ -p-tolyl- δ -oxocapronitrile, γ -methyl- γ -p-bromophenyl- δ -oxocapronitrile, γ -n-propyl- γ -p-chlorophenyl- δ -oxocapronitrile,

5

oxocapronitrile, γ -ethyl- γ -p-isopropyl-phenyl- δ -oxocapronitrile, γ -p-chlorobenzyl- γ -phenyl- δ -oxacapronitrile and γ -n-propyl- γ -p-methoxyphenyl- δ -oxocapronitrile, there was obtained respectively 2,3-dimethyl-3-p-tolyl-3,4,5,6-tetrahydropyridine, 2,3-dimethyl-3-p-bromophenyl-3,4,5,6-tetrahydropyridine, 2-methyl-3-n-propyl-3-p-chlorophenyl-3,4,5,6-tetrahydropyridine, 2-methyl-3-ethyl-3-p-isopropylphenyl-3,4,5,6-tetrahydropyridine, 2-methyl-3-p-chlorobenzyl-3-phenyl-3,4,5,6-tetrahydropyridine and 2-methyl-3-n-propyl-3-p-methoxyphenyl-3,4,5,6-tetrahydropyridine.

Example 7—Preparation of 3-methyl-3-phenyl-6-dimethylamino-2-hexanone.—25 g. (0.134 mole) 2,3-dimethyl-3-phenyl-3,4,5,6-tetrahydropyridine (obtained as in Example 1) was dissolved with cooling in 36 g. (0.7 mole) 90% formic acid. To this was added 26 g. (0.31 mole) 37% formaldehyde. The reactants were heated on a steam bath for approximately three hours. The mixture was then cooled and there was added 25 ml. concentrated hydrochloric acid and the solution was vacuum distilled practically to dryness. There was added 100 ml. water and the resulting solution extracted once with an equal volume of ether. The water solution was then made alkaline with 20% sodium hydroxide solution and a yellow oil precipitated. The oil was taken up in approximately 100 ml. ether and the ether solution dried over potassium carbonate. The potassium carbonate was separated from the ether solution by filtration and the ether evaporated. The residue was a yellow oil which was purified by vacuum distillation. There was obtained 13.8 g. of 3-methyl-3-phenyl-6-dimethylamino-2-hexanone, B. P. 115° C. at 1.0 mm. Hg, n_{D}^{25} 1.5108. The hydrochloride salt melts at 177-8° C.

Example 8—Preparation of 3-ethyl-3-phenyl-6-dimethylamino-2-hexanone.—Following the procedure outlined in Example 7, and substituting for the tetrahydropyridine there used an equimolar quantity of 2-methyl-3-ethyl-3-phenyl-3,4,5,6-tetrahydropyridine (obtained as in Example 2) there was obtained 19 g. of 3-ethyl-3-phenyl-6-dimethylamino-2-hexanone, B. P. 104-6° C. at 0.5-1.0 mm. Hg, n_{D}^{25} 1.5075. The hydrochloride salt melts at 166-7° C.

Example 9—Preparation of 3-n-propyl-3-phenyl-6-dimethylamino-2-hexanone.—Following the procedure outlined in Example 7 and substituting for the tetrahydropyridine there used an equimolar quantity of 2-methyl-3-n-propyl-3-phenyl-3,4,5,6-tetrahydropyridine (obtained as in Example 3) there was obtained 24 g. of 3-n-propyl-3-phenyl-6-dimethylamino-2-hexanone, B. P. 121-128° C. at 0.5 mm. Hg, n_{D}^{25} 1.5062. The hydrochloride salt melts at 193-4° C.

Example 10—Preparation of 3-n-butyl-3-phenyl-6-dimethylamino-2-hexanone.—Following the procedure outlined in Example 7 and substituting for the tetrahydropyridine there used an equimolar quantity of 2-methyl-3-n-butyl-3-phenyl-3,4,5,6-tetrahydropyridine (obtained as in Example 4) there was obtained 22.4 g. of 3-n-butyl-3-phenyl-6-dimethylamino-2-hexanone, B. P. 127-31° C. at 0.5 mm. Hg, n_{D}^{25} 1.5055. The hydrochloride salt melts at 151.5-153° C.

Example 11—Preparation of 3-benzyl-3-phenyl-6-dimethylamino-2-hexanone.—Following the procedure outlined in Example 7 and substituting for the tetrahydropyridine there used an equimolar quantity of 2-methyl-3-benzyl-3-phenyl-3,4,5,6-tetrahydropyridine (obtained as

6

in Example 6) there was obtained 29 g. of 3-benzyl-3-phenyl-6-dimethylamino-2-hexanone, B. P. 157-60° C. at 0.5 mm. Hg. The hydrochloride salt melts at 205-6° C.

Other examples of the invention will be apparent from considering that by substituting for the tetrahydropyridine used in Example 7 equimolar quantities of 2,3-dimethyl-3-p-tolyl-3,4,5,6-tetrahydropyridine, 2,3-dimethyl-3-p-bromophenyl-3,4,5,6-tetrahydropyridine, 2-methyl-3-n-propyl-3-p-chlorophenyl-3,4,5,6-tetrahydropyridine, 2-methyl-3-ethyl-3-p-isopropylphenyl-3,4,5,6-tetrahydropyridine, 2-methyl-3-p-chlorobenzyl-3-phenyl-3,4,5,6-tetrahydropyridine and 2-methyl-3-n-propyl-3-p-methoxyphenyl-3,4,5,6-tetrahydropyridine, there was obtained respectively 3-methyl-3-p-tolyl-6-dimethylamino-2-hexanone, 3-methyl-3-p-bromophenyl-6-dimethylamino-2-hexanone, 3-n-propyl-3-p-chlorophenyl-6-dimethylamino-2-hexanone, 3-ethyl-3-p-isopropylphenyl-6-dimethylamino-2-hexanone, 3-p-chlorobenzyl-3-phenyl-6-dimethylamino-2-hexanone and 3-n-propyl-3-p-methoxyphenyl-6-dimethylamino-2-hexanone.

What is claimed is:

1. The method of preparing 3,3-disubstituted-6-dimethylamino-2-hexanones having the general formula

in which R is selected from the group consisting of an alkyl radical containing from 1 to 12 carbon atoms and a phenalkyl radical, and Y is selected

40 from the group consisting of hydrogen, lower alkyl, halogen and alkoxy comprising hydrogenating an appropriate γ,γ -disubstituted- δ -oxocapronitrile in the presence of Raney nickel catalyst at about 90-100° C. and at a pressure of about 100 atmospheres, heating the tetrahydropyridine so formed with formic acid and formaldehyde until evolution of gas ceases, and recovering the 3,3-disubstituted-6-dimethylamino-2-hexanone so formed.

50 2. In the method as claimed in claim 1 the step comprising hydrogenation of γ,γ -disubstituted- δ -oxocapronitrile in the presence of Raney nickel catalyst at about 90-100° C. and at a pressure of about 100 atmospheres.

55 3. The method of preparing 3,3-disubstituted-6-dimethylamino-2-hexanones having the general formula

60 in which R is selected from the group consisting of an alkyl radical containing from 1 to 12 carbon atoms and a phenalkyl radical, and Y is selected from the group consisting of hydrogen, lower alkyl, halogen and alkoxy comprising dissolving an appropriate γ,γ -disubstituted- δ -oxocapronitrile in anhydrous ethanol, hydrogenating said oxocapronitrile in the presence of Raney nickel catalyst at 90-100° C. and at a pressure of 100 atmospheres hydrogen, cooling the

reaction mixture, separating the catalyst therefrom, removing the ethanol from the reaction product, a tetrahydropyridine, treating the tetrahydropyridine with from 4 to 10 moles formic acid, and 1 to 5 moles formaldehyde per mole of original capronitrile, heating the reaction mixture at 90-100° C. until evolution of gas ceases, and recovering the 3,3-disubstituted-6-dimethylamino-2-hexanone so formed.
